DESIGN FOR A COMBINED LIST FINDER AND CLOCK

Max Marcus, New York, N. Y.

Application June 24, 1938, Serial No. 78,011

Term of patent 3½ years

To all whom it may concern:

Be it known that I, Max Marcus, a citizen of the United States and resident of New York city, in the county of New York and State of New York, have invented a new, original, and ornamental Design for a Combined List Finder and Clock, of which the following is a full, clear, and exact description, reference being had to the accompanying drawing, forming a part thereof.

Fig. 1 is a perspective view of a combined list finder and clock, showing my new design.

Fig. 2 is a perspective view of the same in open position.

Fig. 3 is a side view of Fig. 1.

Fig. 4 is an end elevational view looking in the direction of the arrows 4—4 of Fig. 3.

I claim:

The ornamental design for a combined list finder and clock, as shown.

MAX MARCUS.
